UNITED STATES PATENT OFFICE.

EDWARD ROY MCGRANN, OF MCKEESPORT, PENNSYLVANIA, ASSIGNOR OF ONE-FOURTH TO HARRY C. HERPEL, OF MCKEESPORT, PENNSYLVANIA, AND ONE-FOURTH TO CURT B. MUELLER, OF WEST PARK, OHIO.

GOLF GAME.

Application filed October 15, 1921. Serial No. 507,916.

To all whom it may concern:

Be it known that I, EDWARD ROY MCGRANN, a citizen of the United States, residing at 704 Scott St., McKeesport, in the 5 State of Pennsylvania and county of Allegheny, have invented a new and useful Improvement in Golf Games, of which the following is a specification, the principle of the invention being herein explained, and 10 the best mode in which I have contemplated applying that principle so as to distinguish it from other inventions.

My invention relates broadly to a golf game and more particularly to an appliance 15 intended to make the playing of indoor golf more realistic.

The object is to accomplish the stated purpose by enabling the stroking of a ball after the manner practiced on a regular golf 20 course. What I have termed a golfikin stancer is to be held in an upright position against the floor so as to enable the hand of the player to either turn or tilt it as desired about its space. Slidably and rotatably 25 mounted on the stancer is an operating arm provided at one end with a handle and at its other end with a clamp adapted to engage and hold in a series of adjusted positions the shaft of a miniature golf club.

30 The positioning of the stancer, of the arm with respect to it and of the club with respect to the arm is to be determined by the player with regard for the location of the ball, with respect to its distance from the 35 hole and with consideration of any hazards interposed between it and the hole. Then a flip of the club is to be imparted with the intention of advancing the ball.

Adverting to the drawings:

40 Figure I is a perspective view showing how my appliance might be employed in playing a golf game on the floor of a room.

Figure II is an enlarged perspective view 45 showing how my appliance is to be manually operated.

Figure III is a still further enlarged side elevation of my complete appliance.

Figure IV is a plan view of Figure III.

Figure V is a fragmentary side view on line V—V of Figure IV looking into the 50 direction of the indicating arrows.

Figure VI is a plan view of a part of the clamp for adjustably holding a club.

Figures VII and VIII are a plan view and a side elevation respectively of a modified 55 form of club known as a driver.

Figure IX is a miniature ball.

Figures X and XI are a plan view and a vertical section respectively of a cup.

A room in which use of my invention 60 would be likely to occur includes walls 1 and a floor 2. Laid upon the floor is a strip of carpet or matting 3 which may be considered as a fairway, and at one end of which is deposited an annular cup 4 having a 65 sloping top surface 5 leading to a hole 6. It is desirable to provide the fairway 3 with one or more hazards purposed to obstruct or divert the rolling of a ball therealong. In Figure I is shown a pair of books 70 7 and 8 and an intermediate hump 9, all of which are intended to make less easy the direct progress of a ball 10 from the further end of the fairway 3 toward and into the hole 6 which is large enough to receive the 75 ball.

A stancer 11 is intended to be held against the floor a distance from the point where the ball is first deposited, or thereafter happens to lie, to be determined by the calculation of the individual player. The base 12 of the stancer is preferably fashioned with a spherical bottom 13 in order to facilitate its rocking movement to various tilted positions or ease its turning movement when 80 the handle 14 at its top is moved or turned in a certain direction. The middle section of the stancer 11 is provided with a bore 15 extending therethrough in a direction from side to side for the reception of an actuating arm 16 so as to enable both reciprocal and turning movement of the latter. The arm 16 is of such length that it may project beyond both ends of the bore 15 and carries 85

at one end a wing nut 17 which is to serve as an operating handle.

The other end of the arm 16 carries a circular plate 18 having a central aperture 19 and is fashioned on one side with a series of radial grooves 20 as clearly appears in Figure V. A hook 21 has a screw-threaded shank 22 loosely passed through the aperture 19 and may be drawn in a direction 10 away from that side of the plate 18 on which the grooves 20 appear when a wing nut 23 is screwed onto the shank 22. In this manner a clamp is provided to secure the shaft 24 of either a golf club 25 having an iron 15 head or a wooden club 26 in any one of the grooves 20, the shaft 24 being confined in the selected groove by the bight of the hook 21 as is well shown in Figure IV.

The hole to be played having been laid 20 out and the ball 10 deposited as appears in Figure I, the stancer 11 is placed in a position approximating that there shown. Next, the shaft 24 of a selected type of club is firmly clamped against the plate 18 with the 25 distance of its head 25 from the clamp and its angular relation to the arm 16 determinable at will. Thereafter, the distance of the plate 18 from the stancer 11 may also be varied by movement of the arm 16 in the bore 15 and furthermore the stancer 11 tilted according to the loft it may be desired 30 to impart to the flight of the ball and turned according to the direction it is desired to have the ball follow. Then, if calculations 35 have been properly made, a flip of the head of the club should stroke the ball in a most effective manner, and in any event, something like the "form" of an ideal stroke on a real golf course. It may well be, that 40 some players will prefer to change the order of adjustment of the various parts of my appliance. My invention makes it quite possible to suit the individual fancy in this regard.

45 I claim:—

1. A golf game stancer comprising a support fashioned with a spherically surfaced base and a handle at its top, in combination with a golf club carrier turnably and slidably, mounted upon said support whereby 50 adjustment may be selectively effected to suit the preferred tilt of said support upon its base.

2. An article of the character described 55 consisting of a rigid member adapted at its top to be grasped by the hand and fashioned with a curved bottom surface adapted to be firmly pressed against a support and yet facilitate tilting adjustment about a pivot 60 point of contact with the floor and a golf club carrier adjustably carried by said member.

3. A device of the character described 65 comprising a member adapted to be grasped by the hand and fashioned with a curved

bottom surface to facilitate tilting adjustment about a pivot point of contact with the floor, and a clamp adjustably carried by said member and purposed to engage a toy golf club.

70

4. An appliance of the character described comprising a support adapted to be turned and provided with an opening, a member passed through said opening and adapted to be moved in the same direction as its insertion movement, a clamp carried by said member, and a toy golf club detachably carried by said clamp.

75

5. An appliance of the character described comprising a support adapted to be grasped by the hand and either tilted or turned, and a member carried by said support and provided with a handle, a clamp carried by said member and including a part fashioned with converging grooves, and a toy golf 85 club adapted to occupy any of said grooves and to be secured in a predetermined angular relation to said member.

80

6. An appliance of the character described comprising a support adapted to be tilted 90 and turned, a member mounted for both reciprocal and turning movement on said support, a handle on one end of said member, a clamp carried by the other end of said member, and a toy golf club detachably 95 carried by said clamp.

90

7. An appliance of the character described comprising a support fashioned with a spherically surfaced bottom on which it is adapted to be tilted and turned, a member mounted for reciprocal movement on said support and projecting beyond opposite sides thereof, a clamp carried by one end of said member and including a member 100 having angularly related grooves, and a toy golf club adjustably carried in one of the grooves of said clamp and adapted for both reciprocal and turning adjustment therein.

105

8. An appliance of the character described comprising a support, a clamp carried by said support and including a part fashioned with angularly related grooves, and a toy golf club adapted to occupy any of said grooves and to be secured in a predetermined angular relation to said support.

110

9. An appliance of the character described comprising a support fashioned with radial grooves, a toy golf club including a handle adapted to occupy and be slidably adjusted lengthwise of any one of said grooves and means for securing said club in one of said grooves.

115

10. The combination of a member fashioned with a spherically surfaced bottom on which it is adapted to be held against a base and to be oscillated and turned while in contact with such base, an arm passed through said member so as to be adapted for turning and sliding movements relative thereto and a toy golf club 125 130

adjustably secured to said arm, the arrangement permitting said club to be moved both relatively to and bodily with said arm.

11. A device of the character described comprising a standard, a toy golf club holder mounted for distinct movements relatively to said standard and a toy golf club mounted for distinct movements relative to said holder.
- 10 12. A device of the character described comprising a standard adapted to be manually shifted or held in an upright position upon a floor, a toy golf club holder loosely mounted in a hole in said standard so as to be capable of both reciprocal and rotatable movements on the latter and a toy golf club adjustably supported by said holder.
- 15 13. A device of the character described comprising a member adapted to be grasped by the hand and fashioned with a curved bottom surface to facilitate tilting adjustment about a pivot point of contact with the floor, an arm adjustably connected with said member and a clamp adjustably carried by

said arm and purposed to engage a toy golf club.

14. The combination of a golf game stancer, a toy golf club and a pair of clamping elements adjustably carried by said stancer and adapted to hold said club in a plurality of angularly related positions.

15. The combination of a golf game stancer having an opening, a toy golf club and a connecting member turnable and slideable in said opening, said member connecting said stancer and club to permit of double relative adjustment thereof.

16. An appliance of the character described comprising a stancer, a member mounted thereon for both turning and straight line movement, a toy golf club and a pair of clamping elements carried by said member and adapted to hold said club in various angular and endwise positions of adjustment.

Signed by me, this 12th day of October, 1921.

EDWARD ROY McGRANN.
